Primary Examiner — Darlington Ly*Assistant Examiner* — Katherine A Holbrow(74) *Attorney, Agent, or Firm* — Fitch, Even, Tabin & Flannery LLP(57) **CLAIM**

I claim the ornamental design for a display screen with icon, as shown and described.

DESCRIPTION

The FIGURE is a front view of a display screen with icon according to my new design.

The broken line showing of a display screen is included for the purpose of illustrating portions of the article and forms no part of the claimed design.

1 Claim, 1 Drawing Sheet(56)
